JEWELRY FINDING

J. Neale Burns, 2422 22nd St.,
Newport Beach, Calif. 92660

Filed Oct. 10, 1972, Ser. No. 295,856

Term of patent 14 years

Int. Cl. D11—01

U.S. Cl. D45—19 S

FIG. 1

FIG. 3

FIG. 4

FIG. 2

FIG. 5

FIG. 6

FIG. 1 shows a front perspective view of my ornamental design for a jewelry finding;

FIG. 2 shows a rear perspective view of my invention in the direction of lines 2—2 of FIG. 1;

FIG. 3 shows a front elevation view of my invention;

FIG. 4 shows a view from the underside of my invention along lines 4—4 of FIG. 3;

FIG. 5 shows a sectional view taken along lines 5—5 of FIG. 3; and

FIG. 6 shows a vertical sectional view along lines 6—6 of FIG. 3.

This invention is to be used with ornamental designs such as for a jewelry finding, adornment, and general decor.

I claim:

The ornamental design for a jewelry finding, as shown.
